CLAIM

The ornamental design for a double valance bracket, as shown and described.

DESCRIPTION

FIG. 1 is a perspective view of a double valance bracket showing my new design;

FIG. 2 is a top plan view thereof;

FIG. 3 is a front elevational view thereof;

FIG. 4 is a right side elevational view, with the opposite side being a mirror image thereof;

FIG. 5 is a rear elevational view thereof;

FIG. 6 is a bottom plan view thereof.

FIG. 3 FIG. 4 FIG. 5
